(57) **CLAIM**

The ornamental design for an anti slip nose pad, as shown and described.

DESCRIPTION

FIG. 1 is a perspective view of an anti slip nose pad showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a sectional view which is taken along line 8-8 in FIG. 4.

1 Claim, 8 Drawing Sheets---
